UNITED STATES PATENT OFFICE

2,180,974

REFRIGERATING MACHINE

Leonard W. Atchison and James L. Fletcher,
Schenectady, N. Y., assignors to General Electric Company, a corporation of New York

Application December 1, 1937, Serial No. 177,520

12 Claims. (Cl. 62—102)

Our invention relates to refrigerating machines, and particularly to refrigerating machines having cabinets within which the circulation of air is utilized to maintain a plurality of temperature zones.

The cabinets of refrigerating machines are sometimes provided with an air circulating means such as a fan for producing a circulation of air through the cabinet and over the evaporator or cooling element. When the evaporator is utilized also to provide a freezing zone, substantial quantities of moisture are abstracted from the circulated air and this causes a layer of frost to be formed on the surface of the evaporator. Any foodstuffs placed within the cabinet are thereby dehydrated undesirably. Accordingly, it is an object of our invention to provide a refrigerating machine having a cabinet in which are maintained a plurality of temperature zones and including an improved arrangement for preventing the dehydration of foods placed in one of the compartments and for obtaining effective control of the temperature in that compartment.

Another object of our invention is to provide a refrigerating machine including a cabinet having a plurality of temperature zones and an improved arrangement for utilizing the evaporator of the refrigerating machine to provide a freezing zone and to maintain a relatively high range of temperatures in the food compartment.

Further objects and advantages of our invention will become apparent as the following description proceeds, and the features of novelty which characterize our invention will be pointed out with particularity in the claims annexed to and forming a part of this specification.

For a better understanding of our invention, reference may be had to the accompanying drawings, in which

Fig. 1 is a front elevation view partly in section of a household refrigerating machine embodying our invention; Fig. 2 is a sectional side elevation view on the line 2—2 of Fig. 1, and Fig. 3 is a sectional plan view on the line 3—3 of Fig. 1.

Referring now to the drawings, we have shown a household refrigerating machine comprising a cabinet 10 having an outer wall 11 and an inner wall 12 spaced apart and provided with a body of heat insulation 13 therebetween. Within the cabinet and spaced from the wall 12, we provide a liner 14 of metal or other suitable thermally conductive material forming a food compartment. As clearly shown in Fig. 3, the liner 14 seals the food compartment from the remainder of the in-

terior of the cabinet, a door 15 being provided to close the food compartment and a door 16 being provided at the left of the door 15 to close the other portion of the interior of the cabinet. In order to cool the cabinet, we provide a refrigerant evaporator 17 arranged in the lower portion of the cabinet at one side of the liner 14 and we house the evaporator or cooling element 17 in a sheet metal casing 18. In order to supply refrigerant or cooling medium to the evaporator 17, we provide a condensing unit arranged in a compartment below the thermally insulated food compartment. The condensing unit comprises a sealed casing 19 within which are arranged a motor and a refrigerant compressor, a refrigerant condenser 20 at one side of the casing 19, and a float valve chamber or refrigerant receiver 21. Refrigerant is compressed by the compressor within the casing 19 and is discharged through a connection 22 to the condenser 20 where it is cooled by the circulation of air produced by operation of a fan (not shown) arranged in a shroud 23 and driven by a motor 24. The refrigerant is liquefied within the condenser and flows through a connection 25 to the float valve chamber 21. When a predetermined amount of liquid refrigerant has collected in the chamber 21, a float therein rises and the refrigerant flows through a liquid line 26 to the evaporator 17. The liquid refrigerant within the evaporator 17 absorbs heat from articles placed within the evaporator and from the air circulating thereover, and is vaporized, the vaporized refrigerant collecting in a header 27 and being withdrawn therefrom through a suction line 28 and returned to the compressor within the casing 19. The evaporator 17 is arranged to provide a plurality of freezing chambers within which water, desserts or the like may be frozen. The evaporator comprises two refrigerant circulating sections, an upper section having refrigerant circulating conduits 29 depending from and communicating with the header 27, and the lower section having a plurality of conduits 30 communicating with and depending from a header 31. Refrigerant is admitted to the conduits 29 and 30 through branches of the liquid line 26. The refrigerant vaporized in the lower evaporator rises through an equalizer connection 32 to the header 27. An evaporator similar to that illustrated is described and claimed in Patent No. 2,110,002, granted March 1, 1938, to Chester Lichtenberg, and assigned to the same assignee as the present application. We do not,

therefore, herein claim anything shown or disclosed in the said Lichtenberg application.

In order to circulate air through the interior of the refrigerator cabinet and over the exterior walls of the liner 14 and thereby cool the food storage compartment without undesirably reducing the relative humidity therein, we provide a fan 33 driven by a motor 34 mounted within an opening 35 in the rear wall of the 5 casing 18 which is spaced from the rear wall of the cabinet. The fan 33 is operated to circulate air from the evaporator or freezing compartment around the walls of the liner 14 as indicated by the arrows and over the top of the 10 liner 14 to a compartment or chamber 36 above the evaporator compartment and at one side of the food compartment. The circulating air returns to the evaporator compartment through an opening 37 between the top edge of the casing 18 and the door 16, and also through an opening 38 in the top of the casing 18 at the rear of the evaporator 17. The two inlets 37 and 38 to the freezing compartment divide the air circulating therethrough into two streams. 15

The air entering through the opening 38 passing directly to the fan 33 while the air entering through the opening 37 passes around the walls of the evaporator 17 and is, therefore, cooled before being discharged from the compartment 20 by operation of the fan. The evaporator 17 is, therefore, arranged in the path of only one of the streams of air and the air circulated by the fan 33 is a mixture of air which has been cooled by the evaporator and air recirculated without cooling. We provide doors 39 and 40 on the upper and lower portions of the evaporator to prevent the passage of air through the freezing chambers of the evaporator. The circulated air is, therefore, cooled by passage over 25 the outer walls of the evaporator and substantially no circulation of air is produced within the freezing chambers. The proportion of air in the two streams passing through the evaporator member may be varied by adjusting a damper 41 arranged in a sleeve 38a about the opening 38 to change the effective size of the opening 38. 30

The temperature of the evaporator 17 is maintained within predetermined desired limits by controlling the operation of the compressor, a control device 42 having a thermostatic element 43 in contact with the side of the evaporator 17 being utilized for this purpose. The temperature of the evaporator 17 may, therefore, be maintained below freezing, so that water, desserts and other 35 foods may be frozen within the freezing chamber. It is desirable to maintain the temperature of the air within the food compartment within a range of from 45° F. to 50° F. We, therefore, provide a control device 44 having a thermostatic element 45 arranged within the food compartment in the upper portion thereof, to control the operation of the fan 33, so that air is circulated over the outside of the liner 14 only when it is desired to cool the air within the food compartment. The air within the food compartment is circulated by natural convection, the warmer air rising to the upper portion. For this reason, the control element 45 is placed in the upper portion of the food compartment where it 40 is responsive to the highest temperature therein. Suitable supports, such as grille-like shelves 46, are provided for articles to be cooled within the compartment. The fan 33 is normally operated at substantially constant speed and the rate 45 of cooling of the food compartment will, therefore, vary with the temperature of the evaporator 17. When the evaporator 17 is being utilized to freeze articles placed therein, the temperature thereon may be adjusted to remain very low for a considerable period of time. The air circulated by the fan 33 will, therefore, be cooled to a greater extent and will effect a desired cooling of the liner 14 in a shorter time. In extreme cases, the motor 34 may be required to start and stop the fan 33 at comparatively short intervals. The 5 air admitted through the opening 38 tends to prevent this "short-cycling" of the fan motor and also prevents freezing of food in the compartment 36. The opening 38 may be selected of such size that at the lowest possible temperatures of the evaporator 17, there will be sufficient air admitted through the opening to prevent "short-cycling" of the fan motor. The damper 41 is provided so that when the evaporator 17 is operating at higher temperatures, the amount of air drawn through the opening 38 may be reduced to cause the fan 33 to draw a greater portion of the circulated air over the evaporator 17 where it is cooled. It is, therefore, apparent that the damper 41 may be adjusted to provide satisfactory operating periods of the fan motor 34. The control of the damper may be made automatic by providing a temperature responsive element 41a in the stream of air leaving the fan, the element 41a being connected to close the damper 30 on a rise of the temperature of the air discharged by the fan. 35

The evaporator compartment contains the coldest air, and the air discharged from this compartment, circulates over the liner 14 and thence through the compartment 36. The circulating air, however, does not reduce the temperature of the food compartment within the liner 14 to its own temperature, and the food compartment is, therefore, maintained at a temperature intermediate that of the compartment 36 and the freezing compartment. The compartment 36 provides a convenient place for the storage of bottled goods and the like at temperatures which lie within a range of say, 36° F. to 44° F. 40

Ventilation of the food compartment is sometimes desirable to remove stale air and decrease the tendency of foods to become odiferous. We, therefore, provide an opening 47 in the sealing gasket 48 at the top of the door 15 and also a drain opening 49 at the bottom of the casing 14 which provides a drain for any moisture collecting in the casing and also provides a discharge opening for vitiated air. It will be evident that the air collected within the casing 14 will tend to pass through the drain 49 due to the effect of gravity and some ventilating air will, therefore, be drawn through the opening 47 into the food compartment. 45

Any moisture collecting in the main portion of the cabinet and in the evaporator chamber may be drained out through a drain connection 50. The drains 49 and 50 convey the drain water to a pan 51 mounted on a bracket 52 in the condensing unit compartment below the cabinet. 50

During the operation of the refrigerating machine illustrated, the air in the cabinet will be circulated whenever the temperature of the upper portion of the food compartment rises to a value sufficient to operate the control 44 and start the fan motor 34. Fan 33 will then operate to draw air through the cooling compartment in the two streams from the openings 37 and 38 and to cool the air in the stream passing over the evaporator 17. The operation of the fan 33 55

will maintain a continuous circulation of air through the freezing compartment around the exterior of the liner 14 and through the compartment 36 as long as there is a demand for cooling of the food compartment. If articles are placed within the freezing chambers on the shelves cooled by the conduits 29 and 30, the temperature of the evaporator 17 may be adjusted by operation of the control 42 to a low value for quick or sharp freezing. At such times, the temperature of the evaporator 17 will be considerably lower and the air circulated thereover by the fan 33 will be cooled to a greater extent. If such condition of operation is prolonged, the element 41a may move the damper 41 to increase the effective size of the opening 38 in order to recirculate more of the air without cooling. The mixture of air formed by the intermingling of the streams before their passage over the liner 14 will be at a higher temperature than before movement of the damper and will, therefore, require a correspondingly longer time to reduce the temperature of the air within the food compartment thereby increasing the running time of the fan and preventing "short-cycling" and freezing of food in the compartment 36. Throughout the operation of the refrigerating machine, a small quantity of ventilating air will be drawn into the food compartment and will circulate there-through, a corresponding quantity of cold stale air leaving the compartment through the drain opening 49.

While we have disclosed one embodiment of our invention in connection with a household refrigerating machine, other modifications will readily be apparent to those skilled in the art. We do not, therefore, desire our invention to be limited to the particular construction shown and described, and we intend in the appended claims to cover all modifications within the spirit and scope of our invention.

What we claim as new and desire to secure by Letters Patent of the United States is:

1. A refrigerating machine including a thermally insulated cabinet, means including a liner for providing a food storage compartment within said cabinet, means for circulating air through the interior of said cabinet and over the exterior of said liner, means for dividing into two streams the air circulating through said cabinet, means for reuniting said streams prior to the circulation of said air over said liner, and means including a cooling element arranged to cool the air in only one of said streams for cooling said food compartment.

2. A refrigerating machine including a thermally insulated cabinet, means including a liner for providing a food storage compartment within said cabinet and for preventing the passage of air from the interior of said cabinet to said food compartment, means for circulating air through the interior of said cabinet and over the exterior of said liner, means for dividing into two streams the air circulating through said cabinet, means for reuniting said streams prior to the circulation of said air over said liner, and means including a cooling element arranged to cool the air in only one of said streams for cooling said food compartment.

3. A refrigerating machine including a thermally insulated cabinet, means including a liner for providing a food storage compartment within said cabinet and for preventing the passage of air from the interior of said cabinet to said food compartment, means for circulating air through

the interior of said cabinet and over the exterior of said liner, means for dividing into two streams the air circulating through said cabinet, means for reuniting said streams prior to the circulation of said air over said liner, means including a cooling element arranged to cool the air in only one of said streams for cooling said food compartment, and means responsive to the temperature of said reunited streams prior to circulation over said liner for varying the relative volumes of air in said two streams.

4. A refrigerating machine including a thermally insulated cabinet, means including a liner for providing a food storage compartment within said cabinet and for preventing the passage of air from the interior of said cabinet to said food compartment, means for circulating air through the interior of said cabinet and over the exterior of said liner, means for dividing into two streams the air circulating through said cabinet, means for reuniting said streams prior to the circulation of said air over said liner, means including a cooling element arranged to cool the air in only one of said streams for cooling said food compartment, and means responsive to the temperature of the air within said food compartment for controlling the operation of said air circulating means.

5. A refrigerating machine including a thermally insulated cabinet, means including a liner for providing a food storage compartment within said cabinet, means for providing a cooling chamber within said cabinet outside said food storage compartment, means for circulating air from said cooling chamber over the outside of said liner to cool said food compartment, means cooperating with said last mentioned means for providing two streams of air circulating through said cooling chamber, and means including a cooling element arranged in the path of only one of said streams for cooling said circulated air.

6. A refrigerating machine including a thermally insulated cabinet, means including a liner for providing a food storage compartment within said cabinet and for preventing the passage of air from the interior of said cabinet to said food compartment, means for circulating air through the interior of said cabinet and over the exterior of said liner, means for dividing into two streams the air circulating through said cabinet, means for reuniting said streams prior to the circulation of said air over said liner, means including a cooling element arranged to cool the air in only one of said streams for cooling said food compartment, means responsive to the temperature of the air within said food compartment for controlling the operation of said air circulating means, and means arranged to vary the proportion of air flowing in each of said streams for varying the temperature of said circulating air.

7. A refrigerating machine including a thermally insulated cabinet, means for dividing the interior of said cabinet into a food storage compartment and a freezing compartment and an intermediate temperature compartment, said means including a liner enclosing said food compartment and preventing the passage of air between said food compartment and said other compartments, means for circulating air through the interior of said cabinet from said intermediate compartment through said freezing compartment and thence over the exterior surface of said liner, means for dividing into two streams the air circulating through said freezing compartment, and means including a cooling ele-

- ment arranged in the path of only one of said streams of air for providing a freezing zone in said freezing compartment and for cooling the air circulating through said cabinet.
5. 8. A refrigerating machine including a thermally insulated cabinet, means for dividing the interior of said cabinet into a food storage compartment and a freezing compartment and an intermediate temperature compartment, said 5
10 freezing compartment being arranged below said intermediate temperature compartment, said means including a liner enclosing said food compartment and preventing the passage of air between said food compartment and said 15 other compartments, means for circulating air through the interior of said cabinet from said intermediate compartment through said freezing compartment and thence over the exterior surface of said liner, means including two openings 20 providing communication between said freezing compartment and said intermediate temperature compartment for dividing into two streams the air circulating through said freezing compartment, and means including a cooling element arranged 25 in the path of only one of said streams of air for providing a freezing zone in said freezing compartment and for cooling the air circulating through said cabinet.
9. A refrigerating machine including a thermally insulated cabinet, means for dividing the interior of said cabinet into a food storage compartment and a freezing compartment and an intermediate temperature compartment, said 30 means including a liner enclosing said food compartment and preventing the passage of air between said food compartment and said other compartments, means for circulating air through the interior of said cabinet from said intermediate compartment through said freezing compartment and thence over the exterior surface of said liner, means for dividing into two streams the air circulating through said freezing compartment, means including a cooling element arranged 35 in the path of only one of said streams of air for providing a freezing zone in said freezing compartment and for cooling the air circulating through said cabinet.
- 40 10. A refrigerating machine including a thermally insulated cabinet, means including a liner for providing a food storage compartment within said cabinet, means including a fan for circulating air through the interior of said cabinet and over the exterior of said liner, means for dividing into two streams the air circulating through said cabinet, means for supplying cooling medium to said cooling element, means dependent upon the temperature of said cooling element for controlling said cooling medium supplying means, and means dependent upon the temperature of the air within said food compartment for controlling the operation of said 45 fan.
11. A refrigerating machine including a thermally insulated cabinet, means including a liner for providing a food storage compartment within said cabinet, means including a fan for circulating air through the interior of said cabinet and over the exterior of said liner, means for dividing into two streams the air circulating through said cabinet, means for reuniting said streams prior to the circulation of said air over 50 said liner, means for changing the relative volumes of air circulated in said two streams, means including a cooling element arranged to cool the air in only one of said streams for cooling said food compartment, means for supplying cooling 55 medium to said cooling element, means dependent upon the temperature of said cooling element for controlling said cooling medium supplying means, and means dependent upon the temperature of the air within said food compartment for controlling the operation of said fan.
12. A refrigerating machine including a thermally insulated cabinet, means for dividing the interior of said cabinet into a food storage compartment and a freezing compartment and an intermediate temperature compartment, said 60 means including a liner enclosing said food compartment and preventing the passage of air between said food compartment and said other compartments, means for admitting to said food compartment ventilating air from outside said cabinet and for discharging vitiated air from said food compartment, means for circulating air through the interior of said cabinet from said intermediate compartment through said freezing compartment and thence over the exterior surface of said liner, means for dividing into two streams the air circulating through said freezing compartment, and means including a cooling element arranged 65 in the path of only one of said streams of air for providing a freezing zone in said freezing compartment and for cooling the air circulating through said cabinet.
